UNITED STATES PATENT OFFICE.

CYRIL CHARLES YOUNG, OF KANSAS CITY, MISSOURI, ASSIGNOR TO DOHERTY RESEARCH COMPANY, OF NEW YORK, N. Y., A CORPORATION OF DELAWARE.

GAS-BURNING APPLIANCE.

Application filed November 18, 1926. Serial No. 149,011.

This invention relates to improvements in gas burning appliances and more particularly to appliances suitable for use in furnaces originally designed for burning solid fuel. The conventional type of coal-burning house-heating furnace has a circular fire pot. When gas is burned in a furnace of the fire-pot type it is desirable to deflect the heat against the walls of the fire pot. Inverted cone-like baffling means have been proposed for this purpose, an example of such type being shown in patent to Bigler 884,304. Heat deflectors of the Bigler type are, however, open to the very serious objection that a deflector built to fit one size fire pot cannot be used in a fire pot of substantially different size.

The present invention has for its object to provide a heat deflector of inverted cone-like type which shall be readily adaptable to fire pots of different sizes, low in first cost, easily installed, and otherwise well adapted for the purpose in view.

In accordance with the present invention the heat deflector is made up of a number of elongated bodies or members of wedge-shaped form, these bodies being arranged in overlapping relation in frusto-conical form. By varying the degree of overlap of said members along their adjacent edges the deflector can be quickly and readily adapted to fit fire pots of materially different sizes. In order to more readily adapt the improved heat deflector to different size fire pots, the elongated members from which the deflector is built up are preferably of the special construction shown in the drawings. While it is within the spirit of the invention to make said members from any suitable material it is preferred that they be made from a refractory material which will glow when hot and give forth radiant heat. In addition to the above features there are other details of construction which embody other objects as will more fully appear in the detailed description of the invention.

Referring to the drawings

Fig. 1 is a perspective view of the invention showing it as applied to a hot air furnace. Fig. 2 is a longitudinal broad side elevation of one of similar members from which the improved heat deflector is made up.

Fig. 3 is a longitudinal narrow side or edge elevation of said member.

Fig. 4 is a transverse section on line 4—4 of Fig. 2.

Fig. 5 is an enlarged sectional view taken through the fire pot and burner of Fig. 1 showing the preferred manner of supporting the heat deflecting members on the burner.

Fig. 6 is a transverse section on line 6—6 of Fig. 5.

Fig. 7 is a plan view of the burner shown in Fig. 5.

Fig. 8 is a plan view of the flanged plate on which the heat deflecting members are supported.

The present invention has been shown in connection with the fire pot 10 of a hot air furnace 12. The coal grates normally provided at the base of the fire pot have been removed and a ring gas burner 14 of a more or less conventional type substituted therefor. In the drawings this burner has been shown as supported on a stand 16 resting on the floor of the ash pit of the furnace. Other expedients, however, may be employed for supporting the gas burner in position at the bottom of the fire pot. The usual appliance 18 for supplying the burner with gas is provided.

Suitably mounted on the gas burner is a channelled ring or plate 20 in the channel of which are disposed the individual members making up the baffling device, said members being generally indicated by numeral 22. These members are wedge-shaped in longitudinal broad side elevation and are disposed within the fire pot with their lower ends resting in the channel of the plate 20, the members being inclined outwardly with their upper ends resting against the interior of the fire pot. The manner of disposing the individual heat baffling elements 22 within the fire pot is an important part of the invention. Referring more particularly to Figs. 1 and 6 it will be noted that said members are arranged in two concentric rows, the members of the outer row having their upper ends resting against the interior of the fire pot, said members being arranged in spaced relation to each other. The members of the inner row are also arranged in spaced relation with respect to each other but are so positioned with respect to the members of the outer row that the individual members of the inner row cover the gap between adjacent members of the outer row thereby not only preventing any substantial leakage of hot gases between

the adjacent members but also forming with the fire pot wall a plurality of passages 24 through which the products of combustion may pass upwardly on their way to the flue of the furnace.

The form of the individual baffling members 22 is an important feature of the invention. The individual members in transverse cross-section are generally rhombic in form as shown in Fig. 4. The thickness of the rhomb through points *a* and *b* is substantially the same throughout the length of the body. Due to the fact that the body is made wedge-shaped as viewed in longitudinal broad-side elevation the opposite ends *c* and *d* of the rhombic figure shown in Fig. 4 become more blunt toward the small end of the body. In other words, if the member 22 is viewed in longitudinal edge elevation as in Fig. 3 the edge assumes the shape of an inverted wedge which for convenience of description is designated by reference numeral 26. The small end of the body is preferably bevelled as at 28 in order to facilitate the seating of the body in the channel of the annular supporting plate 20. The upper end of said member is preferably bevelled as at 30 in order to facilitate the positioning of the members within the fire pot.

There are numerous advantages in making the individual heating members of the form indicated. By making them generally rhombic in transverse cross-section (rhombic when the adjacent sides are extended to meet) it will be readily appreciated that the sides of the members opposed to the fire pot conform in a general way with the contour or curvature of the fire pot. The principal advantage, however, is that better joints along the overlapped edges are produced.

By leaning the individual members making up the baffling device outwardly against the fire pot, the flames issuing from the gas burner tend to scour or scrub the adjacent surfaces of said members, and they consequently become very hot. Said members are preferably of a refractory material which will glow when hot and consequently will radiate heat to the adjacent fire pot walls. The sides or the faces of said members which are exposed to the flames are preferably provided with a plurality of knobs or projections 32 in order to effect a more thorough scouring or scrubbing action of the hot gases on the material. Furthermore, these projections quickly become glowing hot and thus begin to radiate heat before the main body of the baffling element has become sufficiently hot to glow. The hot gases pass upwardly between the fire pot wall and the adjacent baffling elements through the passages 24.

The individual baffling elements constructed in accordance with my invention are easily manufactured and are strong and rug-

ged. They also lend themselves to a ready disposal within the fire pot. It will be readily appreciated that a heat baffling device constructed and arranged according to my invention is very readily adaptable to various sized fire pots.

Various changes in details of construction may be made without departing from the spirit of the invention.

What is claimed as new is:

1. The combination with the fire pot of a furnace and a gas burner adapted to direct a ring of flame into the fire pot, of a frusto-conical baffling device flaring outwardly toward the fire pot from within the gas burning portion of the burner whereby the flames issuing from the burner are directed between gradually converging walls formed by said device and the fire pot, said device comprising a plurality of elongated members arranged with their adjacent edges in overlapped relation.

2. The combination with the fire pot of a furnace and a gas burner adapted to direct a ring of flame into the fire pot, of a frusto-conical baffling device flaring outwardly toward the fire pot from within the gas burning portion of the burner whereby the flames issuing from the burner are directed between gradually converging walls formed by said device and the fire pot, said device comprising one set of elongated members arranged in a circular row with their adjacent edges in spaced relation, and another set of like members arranged in a parallel concentric circular row, the members of one set covering the spaces between adjacent members of the other set.

3. The combination with the fire pot of a furnace and a gas burner adapted to direct a ring of flame into the fire pot, of a frusto-conical baffling device flaring outwardly toward the fire pot from within the gas burning portion of the burner whereby the flames issuing from the burner are directed between gradually converging walls formed by said device and the fire pot, said device comprising a plurality of elongated members arranged with their adjacent edges in overlapped relation, said members being substantially rhombic in cross-section when the adjacent sides are extended.

4. The combination with the fire pot of a furnace and a gas burner adapted to direct a ring of flame into the fire pot, of a frusto-conical baffling device flaring outwardly toward the fire pot from within the gas burning portion of the burner whereby the flames issuing from the burner are directed between gradually converging walls formed by said device and the fire pot, said device comprising a plurality of elongated members arranged with their adjacent edges in overlapped relation, said members being substantially rhombic in

cross-section when the adjacent sides are extended and being wedge-shaped in longitudinal broad-side elevation.

5. The combination with the fire pot of a furnace and a gas burner adapted to direct a ring of flame into the fire pot, of a frusto-conical baffling device flaring outwardly toward the fire pot from within the gas burning portion of the burner whereby the flames

10 issuing from the burner are directed between gradually converging walls formed by said device and the fire pot, said device comprising a plurality of elongated members arranged with their adjacent edges in overlapped relation, said members being substantially rhombic in cross-section when the adjacent sides are extended and being wedge-shaped in longitudinal broad-side elevation, the thickness of a member at its middle portion being substantially the same throughout its length.

6. The combination with the fire pot of a furnace and a gas burner adapted to direct a ring of flame into the fire pot, of a frusto-conical baffling device flaring outwardly toward the fire pot from within the gas burning portion of the burner whereby the flames issuing from the burner are directed between gradually converging walls formed by said device and the fire pot, said device comprising a plurality of elongated members arranged with their adjacent edges in overlapped relation, said members being substantially rhombic in cross-section when the adjacent sides are extended and being wedge-shaped in longitudinal broad-side elevation, the thickness of a member at its middle portion being substantially the same throughout its length, and the wider end of each member having downwardly sloping sides.

7. In combination with a fire-pot of a furnace and a gas burner adapted to direct a substantially annular flame into the fire-pot, of a substantially frusto-conical baffling device, flaring outwardly toward the fire-pot from within the gas burning portion of the burner whereby the flames issuing from the burner are directed against the baffle and forced to pass between gradually converging walls formed by the baffling device and the fire-pot, said device comprising a plurality of elongated baffling elements mounted with the edges of adjacent elements overlapping.

8. In combination with a fire-pot of a furnace and a gas burner adapted to direct a ring of flame into the fire-pot, of a frusto-conical flame deflecting device inverted with respect to said burner, said device comprising a plurality of members made up of a refractory material which becomes highly luminous when heated to emit radiant heat, the surface of said members being covered with projecting portions to increase the radiant heat emanations.

9. In a furnace fire-box, an apparatus com-

prising a burner for projecting a flame thereinto and a baffle supported in said fire-box for directing the flame from said burner against the sides of said fire-box to be heated, an improved baffle which comprises a plurality of elongated baffle elements substantially wedge-shaped in longitudinal front elevation and substantially rhombic in transverse section.

10. In a furnace combination, comprising a fire-box, a burner mounted therein, and a flame deflector formed of a plurality of similar elements adapted to cause the flame from said burner to wash the inner sides of said fire-box, an element for said deflector of heat-resisting material, substantially wedge-shaped in longitudinal front elevation, and having a greater thickness along its longitudinal mid-portion than along its longitudinal edges.

11. In a furnace combination, comprising a fire-box, a burner mounted therein, and a flame deflector formed of a plurality of similar elements adapted to cause the flames from said burner to wash the inner sides of said fire-box, an element for said deflector of heat-resisting material, having a length greater than its width, ends of unequal width, and projections covering a substantial portion of the area of one side thereof.

12. A furnace structure comprising a fire-box, an annular burner mounted in said fire-box, a baffle-supporting means including an annular ridge for supporting and retaining a baffle inside said burner, a baffle mounted on said support and comprising a plurality of elongated baffling members substantially rhombic in cross section, and means for holding said baffling members in an inclined position over said burner whereby the flames from said burner are directed against the side walls of said fire-box.

13. The combination with the fire-box of a furnace and an annular burner adapted to project a substantially annular flame into said fire-box, of a substantially annular flame deflector having its lower end supported inside said annular burner and its upper end supported by the side walls of said fire-box, said deflector comprising a plurality of elongated baffle members, the adjacent edges of which overlap, whereby said deflector may accommodate itself to changes in size of the fire-box.

14. The combination with the fire pot of a furnace having a fluid fuel burner adjacent a side wall thereof, of a flame deflecting baffle supported adjacent said burner opposite said wall, said baffle extending above and over said burner toward said wall to deflect the flame from said burner into contact with said fire pot wall, said baffle comprising a plurality of overlapping elements.

In testimony whereof I affix my signature.
CYRIL CHARLES YOUNG.
